UNITED STATES PATENT OFFICE.

LOUIS C. LE COUNT, OF LOS ANGELES, CALIFORNIA.

WARDROBE SOFA-COUCH OR OTHER RECEPTACLE.

SPECIFICATION forming part of Letters Patent No. 695,818, dated March 18, 1902.

Application filed November 16, 1899. Serial No. 737,232. (No model.)

To all whom it may concern:

Be it known that I, LOUIS C. LE COUNT, a citizen of the United States, residing at Los Angeles, in the county of Los Angeles and State 5 of California, have invented a new and useful Improvement in Wardrobe Sofa-Couches or other Receptacles, of which the following is a specification.

The object of this invention is to provide a 10 simple, cheap, and strong wardrobe-couch which can be opened from either side and in which the cover or top part can be locked when closed and will be rigidly held with relation to the box or bottom when in the open 15 position. The invention is also applicable for a trunk or chest.

An object of my invention is to provide simple and superior means by which to automatically and positively hold the top of the sofa 20 firmly in position, so that the sofa may be handled by lifting on said top at either end, and this I accomplish by the means herein-after fully set forth.

My invention is especially applicable for a 25 sofa or divan forming a receptacle and intended to stand against the wall, for the reason that it is desirable for such devices that the divan can be reversed in order that the wear may alternately come upon one or the 30 other side or edge.

My invention comprises a base member, a top member on the base member, a hinge pivoted at one end to one side of the base member and at the other end to the top member 35 at the other side of the device, and hinged fastening devices for the opposite sides of the device, respectively, detachably hinging the opposite sides of the top to the corresponding sides of the base.

40 The accompanying drawings illustrate my invention.

Figure 1 is a view of the unupholstered frame of my newly-invented wardrobe-couch. The top is shown thrown open. Fig. 2 is a 45 cross-section of the couch on line 2 2, Fig. 1. The top is shown closed in solid lines. Dotted lines indicate the two positions of parts when the top is thrown open from either side. Fig. 3 is a detail of the joint of the 50 brace. Fig. 4 is a sectional detail illustrating one of the locks.

1 indicates the sofa-bed box.

2 indicates the cover or top fitted to the box and hinged thereto by hinges 3 3' 4 4'. The hinges 3 and 3' are each pivoted by one end 55 to the box at one side of the bed, as indicated at 5 5', and to the top at the other side of the bed, as indicated at 6 6'. The hinges 4 4' are each pivoted at the other end to the box at the other side of the bed, as indicated at 7 7', 60 and to the top 2 at the first-mentioned side of the bed, as indicated at 8 8'.

9 9' indicate the two members of a jointed brace, which members are pivoted to each other, as at 10, and are pivoted to the end 65 pieces 11 12 of the box and cover, respectively, at the mid-width of the bed, as indicated by the pivots 13 14.

15 indicates the stop, which prevents the jointed brace from bending downward, so 70 that when the cover or top 2 is thrown open, as shown in Fig. 1 and indicated by dotted lines in Fig. 2, and the brace is thrown into its extended or straight position the top 2 will be held rigid with relation to the bottom 75 or box 1.

In practical use the bed will be upholstered in any suitable manner, (not shown,) and the cover can be raised from either side, and when brought into the fully-opened position 80 the brace will fall into its extended position, (shown in Fig. 1,) and the top will be held rigidly against any upward, downward, or lateral pressure, so that the bed may be moved by means of the uplifted cover, as well 85 as by the box, and it is immaterial from which side the couch is opened, the jointed brace operating with equal effect in either instance. Hasps 16 16' are fastened to the top at opposite sides thereof, and locks 17 17' 90 therefor are provided on the opposite sides of the box, so that when the cover is down it can be securely locked by the two locks. The cover can be opened from either side by unlocking the lock on that side only. 95

It is to be understood that the pivoted bars 3 3' are virtually a single hinge in operation, but that the two members 3 3', being placed at the ends of the couch, respectively, give a maximum strength and rigidity with a minimum weight. The same holds true with regard to the hinge formed by the pivoted members 4 4'. The pintles or pivots *p* of all the hinges on either side, including that of the

hasp, are all in line with each other when the cover is closed on that side.

The form of the oppositely-arranged locking devices 16 17 and 16' 17' for detachably securing the box and top together may be varied at the pleasure of the constructor without departing from the spirit of this invention.

By placing the locking devices at the opposite sides of the receptacle and using hinged hasps, as shown, the pintles *p* of which are in line with the pintles of the hinges on that side, the top will open freely when either of the locks is unlocked. By reason of the hinges 3 4 at one end of the box and the hinges 3' 4' at the other end of the box when the top is thrown open, as shown in Fig. 1, the ends of the top are firmly held against displacement by the hinges 3 4 and the hinges 3' 4', respectively, regardless of which direction the top is opened, so that when the top is open and is left open there is no danger of racking the hinges and the parts will remain positively in the relative positions shown.

25 By the use of a hasp fastened to one member 2 and a lock fastened to the other member 1 the sofa-top may be securely locked and indiscriminately opened from either side by unlocking the appropriate lock.

30 What I claim, and desire to secure by Letters Patent of the United States, is—

1. A sofa-bed comprising a box; a top fitted to the box; hinges hinging said top to said box, one of which hinges is pivoted by one end to the sofa-box at one side of the bed and pivoted at the other end to the sofa-top at the other side of the bed and the other hinge being pivoted to said box at said other side of the bed and to said top at the first-mentioned side of the bed; and an adjustable reversible brace for holding the top at an incline in either direction.

2. The combination of a box-body; a top fitted to the box-body; hinges 3, 4, at one end of the box and body, one of which hinges is pivoted by one end to the box-body at one side of the box and pivoted at the other end to the box-top at the other side of the box, the other hinge 4 being pivoted to said box-body at said other side of the box and to the top at the first-mentioned side; hinges 3', 4', at the other end of the box, one of which hinges is pivoted by one end to the box-body at one side of the box and pivoted at the other end to the top at the other side of the box and the other hinge being pivoted to the box at said other side of the box and to the top at the first-mentioned side, substantially as set forth.

3. A sofa-bed comprising a box; a top fitted to the box; hinges hinging said top to said box; one of which hinges is pivoted by one end to

the sofa-box at one side of the bed and is pivoted at the other end to the sofa-top at the other side of the bed and the other hinge is pivoted to said box at said other side of the bed and to said top at the first-mentioned side of the bed; a hasp and a lock detachably securing the box and top together at one side; and a hasp and a lock detachably securing the box and top together at the other side. 7c

4. The combination of a box; a top fitted to the box to form a closed receptacle; a hinge pivoted at one end to one side of the box and at the other end to the top at the other side of the receptacle; a hinge pivoted at one end to the box at said other side of the receptacle and to the top at the first-mentioned side of the receptacle; and a jointed brace pivoted to an end piece of the box and to an end piece of the cover at the mid-width of the receptacle. 75

5. The combination of a box; a top fitted to the box to form a closed receptacle; a hinge pivoted at one end to one side of the box and at the other end to the top at the other side of the receptacle; a hinge pivoted at one end to the box at said other side of the receptacle and to the top at the first-mentioned side of the receptacle; a jointed brace pivoted to an end piece of the box and to an end piece of the cover at the mid-width of the receptacle; and oppositely-arranged locking devices for detachably fastening the box and top together. 85

6. A base member; a top member on the base member; a hinge pivoted at one end to one side of the base member and at the other end to the top member at the other side of the device; a hinge pivoted at one end to the base member at said other side and to the top member at the first-mentioned side; hinged means at one side of the device constructed to detachably secure the base and top members together; and hinged means at the other side constructed to detachably secure the base and top members together. 95

7. A base member; a top member on the base member; a hinge pivoted at one end to one side of the base member and at the other end to the top member at the other side of the device; and hinged fastening devices detachably hinging the opposite sides of the top member to the corresponding sides of the base member. 100

In testimony whereof I have signed my name to this specification, in the presence of two subscribing witnesses, at Los Angeles, California, this 10th day of November, 1899.

LOUIS C. LE COUNT.
